UNITED STATES PATENT OFFICE.

RICHARD D. NILEON, OF BELL, PENNSYLVANIA.

CAN-OPENER.

1,372,899.

Specification of Letters Patent. Patented Mar. 29, 1921.

Application filed September 11, 1920. Serial No. 409,739.

To all whom it may concern:

Be it known that I, RICHARD D. NILEON, a citizen of the United States, residing at Bell, in the county of Somerset and State of 5 Pennsylvania, have invented certain new and useful Improvements in Can-Openers, of which the following is a specification.

This invention relates to can openers and more particularly to an improved apparatus 10 for opening metallic shoe polish boxes and similar containers.

The primary object of the invention is to provide a simple and inexpensive opener attached without the use of rivets or bolts 15 and in a manner that will permit the contents of the box to remain air tight.

Other objects of the invention will appear upon consideration of the following detail 20 description and accompanying drawings, wherein:—

Figure 1 is a front elevation of the device as applied to a shoe polish box of the conventional form.

Fig. 2 is a side elevation partly in section, 25 and

Fig. 3 is a detail perspective view of the opener detached.

Referring to the drawing by numerals, the 30 container 1 is provided with a removable cover 2, and the marginal edge of the latter normally contacts with an annular flange 3 formed on the container.

An extension 4 is provided on the cover 35 and this extension projects from the marginal edge of the cover and is provided with a circular opening 5. The extension forms a tab which is adapted to be bent to any desired shape whereby the opener proper may be mounted in position. The opener comprises a member 5 formed of a length of wire 40 bent as at 6 intermediate its ends and folded upon itself to form a finger press 7 the latter being disposed at an angle to the shank 8 which is formed by parallel portions of the 45 wire. The terminals of the wire are disposed at an angle with respect to each other and diverge from the end of the shank 8 to form the pressure arms 9 which are properly curved so that the ends 10 may engage the 50 annular flange 3.

The opener or member 5 is attached by inserting the shank 8 through the opening in

the tab 4 and the tab is preferably curved as indicated in Fig. 2 so that the shank will be extended outwardly at an angle while the 55 terminals 10 of the pressure arms 9 will be permitted to engage the annular flange 3. This permits the marginal edge of the opening in the tab to form a fulcrum whereby the shank 8 acts as a lever and an inward pressure on the finger press 7 will cause the 60 pressure arms 9 to exert a downward pressure on the annular flange 3 whereby the cover and container will be separated.

Minor changes may be made in the details 65 of construction without departing from the spirit of the invention or the scope of the claims hereunto appended.

What I claim is:—

1. In combination with a container having 70 a removable cover and provided with an annular flange, of a tab formed on the cover and provided with an opening, an opener member comprising a shank arranged in the opening in the tab to fulcrum on the edge of 75 the opening for forming a lever, and diverging pressure arms formed on the shank and adapted to engage the flange at points spaced from the said tab.

2. In combination with a container having 80 a removable cover and provided with an annular flange, of a tab formed on the marginal edge of the cover and curved upwardly in spaced relation to the cover and provided with an opening, an opener member 85 having a shank mounted in the opening to fulcrum on the edge of the opening, one edge of the shank being provided with a finger press whereby the shank may be manually tilted, and pressure arms formed 90 on the shank and diverging therefrom to engage the annular flange at points spaced from the said tab.

3. In combination with a container having 95 a removable cover and provided with an annular flange, of a tab formed on the marginal edge of the cover and curved upwardly in spaced relation to the cover and provided with an opening, an opener member having 100 a shank mounted in the opening to fulcrum on the edge of the opening, one edge of the shank being provided with a finger press whereby the shank may be manually tilted, and pressure arms formed on the shank and

diverging therefrom to engage the annular flange at points spaced from the said tab, the said tab being curved whereby the shank normally extends outwardly at an angle, the said pressure arms being curved from the shank whereby a pressure on the said finger press will cause the said shank to fulcrum in the opening and exert a downward

pressure on the said pressure arms to separate the cover from the said container. 10

In testimony whereof, I have affixed my signature in the presence of two witnesses.

RICHARD D. NILEON.

Witnesses:

C. A. WHIPPERMAN,

JOE FIGGE.
